UNITED STATES PATENT OFFICE.

GEORGE A. KEENE, OF LYNN, MASS., ASSIGNOR OF ONE-HALF TO CHARLES W. MELCHER AND GUSTAVUS N. SPINNEY, OF SAME PLACE.

WINDOW-WASHER.

SPECIFICATION forming part of Letters Patent No. 258,926, dated June 6, 1882.

Application filed February 23, 1882. (No model.)

To all whom it may concern:

Be it known that I, GEORGE A. KEENE, of Lynn, in the county of Essex and State of Massachusetts, have invented new and useful 5 Improvements in Window-Washers, of which the following is a specification.

This invention relates to that class of window-washers adapted to hold and employ sponge or other soft or fibrous material, but 10 does not apply to bristle brushes.

In the accompanying drawings, in which similar letters of reference indicate like parts, Figure 1 is a view of a window-washer embodying my invention. Fig. 2 is a central vertical section.

A is a stiff or rigid back or shell, provided with an opening, *a*, in its upper portion, the said back being made preferably of metal.

B is an elastic mouth-piece, usually made of rubber, having a central opening, *B'*, and provided at or near its outer edge with an annular bead or lip, *b*, by means of which the elastic mouth-piece is easily held in place, as shown, upon the edge of the rigid back and readily 25 removed therefrom, if desired. The mouth-piece is made of such a size that it will stretch over the back A sufficiently to be firmly held thereupon.

C is the sponge, which is placed in the position shown by crowding a minor portion through the opening *B'* into the chamber formed by the back A and mouth-piece B, the major portion remaining outside. The mouth-piece, being elastic, does not tear the sponge, 35 and at the same time affords sufficient friction

to prevent the sponge from being moved from its position.

D is a ring or holder, into which the pole E is thrust for the purpose of elevating the device, said holder having a closed shank, *D'*, 40 and a base, *D''*, which is riveted to the back A.

When the window-washer is plunged in a bucket of water the water flows into the chamber formed by the back A and mouth-piece B, which thus becomes a reservoir of supply for 45 the sponge as it is used. This chamber is practically tight, owing to the elastic mouth-piece provided with the bead *b* and the opening *a* being on the upper side of the back A, no water is wasted. The shape of the holder 50 D imparts to it sufficient spring to hold the pole E firmly when it has been well crowded in, and the holder itself obviates the necessity of perforating the back in order to insert the pole therein.

Having thus fully described my invention, what I claim, and desire to secure by Letters Patent, is—

The herein-described improved window-washer, consisting of the elastic mouth-piece 60 B, provided with the central opening, *B'*, and bead *b*, the rigid back piece or reservoir, A, provided with the inlet-hole *a*, and the pole-holder D, all combined and arranged substantially as and for the purpose set forth.

GEORGE A. KEENE.
